ELECTRICALLY DRIVEN COMPRESSOR

Georg Székely, Graz, Austria

Application February 11, 1935, Serial No. 5,916
In Austria February 26, 1934

1 Claim. (Cl. 230—55)

This invention relates to electromagnetically driven compressors or vacuum pumps of the type in which a resiliently mounted compressor member is driven by the vibrating armature of an alternating current electromagnet, and in which the entire vibrating system is tuned accurately or approximately into resonance with the alternating magnetic field which sets up and maintains the vibrations of the system, and has for its object to improve the resonance conditions at a certain output, and also to extend the range of output within which a favorable working condition prevails.

What has hitherto stood in the way of the employment of compressors of this description has been the drawback that the most favorable resonance conditions are only realized when working to a certain definite end pressure, and that the deflection or throw of the vibrations falls off very considerably when the end pressure deviates but very slightly from the ideal. The present invention is based upon recognition of the fact that this disadvantageous behaviour is largely due to the linear characteristic of the vibrating means and resilient elements hitherto usual in the drive employed in such devices, with the result that on alteration of the pneumatic force or resistance there is brought about an alteration in the resultant spring force acting upon the vibrating mass which is sufficient to destroy the state of resonance.

In order to overcome this unfavorable influencing of the state of resonance conditioned by the curvature of the compression characteristic, the present invention proposes the employment of spring means for the vibrating system which have a non-linear curve for the power developed expressed as a function of the course. It thus becomes possible, more particularly when the characteristic of the spring means employed is upwardly curved, to bring about a condition of vibration which approximates far more closely to the character of harmonic oscillations than does the condition of vibration set up with the employment of springs of linear characteristic. Compressors constructed in accordance with the invention thus show a more favorable state of working, when the output is adjusted to a certain pressure, than the hitherto known compressors, since resonance is invariably far more easily realized in a harmonically vibrating system than when the vibration is non-harmonic or pseudo-harmonic. A further advantage of the invention which is of particular importance is that the mean rise of the resultant spring characteristic changes less, when working to different end pressure, with the employment of springs of non-linear than with the employment of springs of linear characteristic, with the result, under practical working conditions, that the state of resonance is

maintained over a wider range of end pressures than has hitherto been the case.

As springs of non-linear characteristic it is advisable to employ conical springs which are so made that, when stressed, the lower turns become gradually applied to the supporting foundation, so that the number of effective turns diminishes and the power increase is augmented per unit of depression. The non-linear characteristic of the spring means employed can, however, also be obtained in other ways, for example by the use of materials the natural resiliency of which possesses the desired non-linear character, such as is the case for example with vulcanized rubber.

A form of construction for a compressor unit in accordance with the invention is shown, by way of example, in the accompanying drawings, in which:—

Fig. 1 is a sectional view of the compressor unit;

Fig. 2 is a side view of the same taken partly in section of Fig. 1;

Fig. 3 is a plan view of the same;

Fig. 4 shows a modified construction of the spring means;

Fig. 5 is a graphic representation of output curves.

In the constructional example shown in Figures 1 to 4 of the drawings 1 denotes the electromagnet which drives the compressor, the coil 2 of this magnet being traversed by current derived from an alternating current main and thereby caused to exert upon the armature 3 an attraction which fluctuates periodically in intensity. The electromagnet 1 has a circuit in iron which is as far as possible closed, in order to provide maximum electromagnetic output with minimum weight and space requirement. For this same reason the number and size of the air gaps 4, 4', 4'' which interrupt the iron circuit are kept down to a minimum, and the same end is also served by the sloping of the air gaps 4' and 4'' relatively to the direction of vibration of the armature 3.

To the armature 3 is attached the lower end of the bifurcated connecting rod 5 which is made up of laminated material, and which is provided at its upper end with the arched or cambered base plate 6 of the piston. The body 7 of the piston, which is made of rubber, is attached to this plate 6 by means of the embedded and vulcanized-in ring 8 and of the clamps 9. The marginal portion 7a of the body 7 of the piston is of slight thickness so that it is in the nature of a diaphragm, and is clamped, together with the remaining parts of the compressor, in a ring 10 supported in the uprights 11 of the framework of the unit. The hitherto described parts of the vibrating system, namely the armature 3, the piston 7, and the connecting rod 5, should be made

as light as possible, in order to reduce inertia resistance to a minimum, and this fact is taken account of in the shaping and construction of these parts.

5 The base plate 6 of the compressor piston is resiliently supported against the stationary part of the unit by means of a block of rubber 13 which is supported on a cross head 12 bridging the uprights 11. This rubber block 13 is a resilient massive body of elastic material which can be tuned to the desired frequency by suitable shaping, and the characteristic curve of which is non-linear and likewise capable of being influenced in a desired sense by suitable shaping 10 of the block. In lieu of this elastic body 13 it is also possible to employ a tapered helical spring 13a as the supporting or bearing spring of the vibrating system, as indicated in Fig. 4. In designing the springing means employed for the 15 vibrating piston care must also be taken to make this spring, which likewise pertains to the totality of the vibrating system, as light as possible in weight. In order to allow for compensation of any alteration in the initial tension of the 20 spring means 13 or 13a which may occur in the course of use, and thus to obviate any alteration of the inherent frequency or characteristic of these means, and also to admit of accurate adjustment of the initial tension of the spring 25 means, the cross head 12 is adjustable upon the uprights 11 by means of nuts 14. The rubber block 13 is prevented from shifting its position by the provision of centering studs 15 and 15'.

Between the compressor piston 7 and the cover 30 16, which is disposed opposite the same and is likewise clamped peripherally in the ring 10, there is enclosed the working chamber 17 of the compressor in which the intake, compression, and expulsion of the working medium is effected. 35 In the cover 16 there are arranged the suction and the pressure valve of the compressor, so that the vibrating piston comprises no valve parts to add to its total mass. The employment of an independently acting suction valve necessitates, 40 however, that its moving parts be so constructed that they are capable of keeping up with the rapid working rhythm of the compressor according to the invention. It is therefore advisable to make the suction valve disk—and the same applies also to the pressure valve disk—as 45 light as possible in weight, and to make it of such shape that it can open and close with the frequency of the piston vibration or with even higher frequency. In the constructional example shown in the drawings this result is achieved 50 by the use of a rubber suction valve disk 18 which is thickened in the middle so as to be of lenticular shape, and the marginal portion of which covers over the suction apertures 19 provided in the cover 16. The suction valve disk 18 is attached 55 to the cover 16 by means of a screw 20 which ensures the requisite initial tension of the disk. The pressure valve 21 takes the form of an annular diaphragm provided with apertures 22 which 60 are disposed in off-set relation to corresponding apertures 23 in the cover 16.

70 The cover 16 of the compressor is so shaped that, when the suction valve disk 18 is inserted in position, the clearance, provided the stroke of the piston is sufficiently long, is reduced to a minimum. Given such designing of the working chamber, it becomes possible, by suitable tuning of the inherent frequency of the vibrating system to the frequency of the magnetic force and

5 by correct dimensioning of the stroke-limiting counterforces, to provide a stroke volume of the compressor member which practically completely fills out the working chamber of the compressor. Over the plate 16 there are provided the suction chamber 27 with the suction pipe connection 24, and the compression chamber 25 with the compression pipe connection 26. The hoods 28 and 29 enclosing these chambers, respectively, are attached to the cover 16 and to the ring 10, respectively, and can readily be detached, together with the cover 16, after slackening of the screws 30. The electromagnet 1 and the uprights 11 rest upon feet 31 and 32 which are preferably made of sound- and shock-absorbing material.

10 The non-linear characteristic of the spring means associated with the piston not only improves the character of the vibrations, but also helps to prevent the length of the compressor stroke from being in general influenced by the output of the compressor to any appreciable extent, since the resonance once set is maintained in the various working states of the compressor.

15 This will be clearly understood by having reference to Fig. 5 in which the ordinates give the output of the compressor (in litres per hour) referred to the state at suction, and the abscissae the end excess pressure (in atm.) of the compressed air. The broken line I represents the output characteristic obtained in a particular case with a compressor having springing means of linear characteristic; after replacement of this spring by a spring of non-linear characteristic there was obtained the more favorable curve represented by the full line II.

20 In Figs. 1 and 2 of the drawings there is shown the lowest position of the vibrating system (piston and armature) under normal working conditions. If under exceptional working conditions the maximum amplitude of vibration should happen to become exceeded, the increasing of such a tendency beyond the admissible limit is prevented by the lower surface 33 of the armature coming in contact with the opposite surface 34 on the core of the electromagnet, or by the body 7 of the piston striking against the cover 16. Related subject matter was described in applicant's abandoned application Serial No. 25 701,140, filed December 6, 1935.

25 I claim:

An electromagnetically driven compressor or vacuum pump having, in combination, an electromagnet comprising a stationary magnet body, a coil arranged thereon for energization by an alternating electrical current of given frequency and a vibratile armature in position to be attracted by said magnet body upon energization of said coil, a reciprocating compressor member 30 connected to said armature and forming therewith a freely oscillating unit, and resilient restoring means connected to said unit so as to resist its deviation from a given position and tuned to a natural frequency which causes the oscillation of the unit to be substantially in resonance with the periodic force of attraction of the electromagnet, said resilient means comprising a conical helical spring arranged for having its effective number of turns reduced and, accordingly the coefficient of resilience increased when the load acting upon the spring is increased.
